(57) **CLAIM**

The ornamental design for connector, as shown and described.

DESCRIPTION

FIG. 1 is a perspective view of the top, front, and right side of the connector;

FIG. 2 is a perspective view of the bottom, front, and left side of the connector;

FIG. 3 is a perspective view of the top, rear, and left side of the connector;

FIG. 4 is a front view of the connector;

FIG. 5 is a rear view of the connector;

FIG. 6 is a left side view of the connector;

FIG. 7 is a right side view of the connector;

FIG. 8 is a top view of the connector; and,

FIG. 9 is a bottom view of the connector.

The broken lines in FIGS. 1-9 show portions of the connector that form no part of the claimed design.
